(57) **CLAIM**

The ornamental design for a filter cap, as shown and described.

DESCRIPTION

FIG. 1 is a front perspective view of a filter cap showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines represent structure or features which form no part of the claimed design; the broken lines themselves form no part of the claimed design.

The dot-dash broken lines represent boundaries of the claimed design; the dot-dash broken lines themselves form no part of the claimed design.

1 Claim, 4 Drawing Sheets**US D782,000 S**
